UNITED STATES PATENT OFFICE.

FRANK C. DORMENT, OF DETROIT, MICHIGAN, ASSIGNOR TO WIRELESS VIBRATOR COMPANY, OF DETROIT, MICHIGAN, A CORPORATION OF MICHIGAN.

MASSAGE-VIBRATOR.

1,102,885.

Specification of Letters Patent. Patented July 7, 1914.

Application filed April 15, 1913. Serial No. 781,136.

To all whom it may concern:

Be it known that I, FRANK C. DORMENT, a citizen of the United States of America, residing at Detroit, in the county of Wayne and State of Michigan, have invented certain new and useful Improvements in Massage-Vibrators, of which the following is a specification, reference being had therein to the accompanying drawings.

10 This invention relates to a massage vibrator and to an arrangement thereof whereby any portion of the patient may be readily treated either by the patient himself or an attendant and whereby the nature of the 15 vibration may be varied at the will of the operator.

The invention consists in the matters hereinafter set forth and particularly pointed out in the appended claims.

20 In the drawings, Figure 1 is a view, partially in elevation and partially in longitudinal section, of a vibrator that embodies features of the invention; Fig. 2 is a view of the upper end portion of the barrel with 25 the cap removed; Fig. 3 is a view in detail of an eccentric pintle connection for a wobble shaft; Fig. 4 is a view in elevation of the upper end portion of the barrel with an attached massage head; and Fig. 5 is a view 30 in detail showing a modification of the vibrating means.

As herein shown in preferred form a cylindrical barrel 1 is mounted on a head 2 from which an axial holding handle 3 extends. A cap 4 on the upper end of the barrel has a boss 5 with angularly disposed sockets, in any of which the stem 6 of a massage implement 7 may be secured by means of a thumb screw 8. The implement 40 7 may, of course, be of any preferred design for application to the body.

A weight 9 is eccentrically secured on a shaft 10 that is disposed transversely in the casing. A thrust collar 11 at one end of 45 the shaft and an adjustable bushing 12 at the other end provide for adjustment and for take up in case of wear. A crank shaft 13 with handle 14, is adjustably secured on the outer end of the main drive shaft 38. The latter is operatively connected as 50 through a gear 15, pinion 16, countershaft 17, intermediate gear 18 and follower pinion 19 with the weight shaft 10 to drive the latter at a relatively high speed in relation

to the movement of the handle 14. Any preferred form of driving mechanism that produces the required velocity of movement of the weight shaft may be used in place of the gears, pinions and intermediate shaft. Suitable end thrust bushings 20 are used to properly journal the main and countershafts in.

A sleeve 22 in axial alinement with the shaft 10 is detachably secured, as by screw-threaded engagement with a boss 23 on the side of the casing. A cap 24 removably secured on the outer end thereof coöperates with a race-way 25 or annular bearing in the sleeve to retain a spherical bearing 26 intermediate the ends of a wobble shaft 27. A pintle 28 on the inner end of the latter 70 engages an eccentrically disposed socket 29 in the proximate end of the shaft 10. A massage member 30 is removably secured on the outer end of the wobble shaft. In this construction the shaft 10 not only swings 75 the weight 9 but also operates the wobble shaft when the latter is attached. In order that the influence of the weight 9 may be eliminated, the construction indicated in Fig. 5 is used. In such instance a weight 80 shaft 31 has a peripheral flange 32 against which a collar 33 of a pendulum weight 34 may be forced by a thrust ring 35 so that the weight may be locked to turn with the shaft 31. Preferably the collar 35 is shifted 85 by a hand screw 36 in screwthreaded engagement in an axial socket in the shaft 31, the inner reduced end portion thereof having a peripheral groove that engages the inner end portions of radial studs 37 in the 90 thrust collar. Thus the weight may be allowed to hang free when the wobble shaft is mounted on the casing in gear with the shaft 31.

The handle is comparatively heavy in 95 comparison with the outer portion of the casing, so that, because of the relation of the mass of the handle to that of the casing, the vibrations occur mainly at a point remote from the handle which they do not 100 effect.

In operation the rapid revolution of the unbalanced weight on the weight shaft imparts vibrations to the massage member mounted on the barrel cap so that the member produces the desired effect when applied to the part to be treated. As the angle of the massage member in relation to the barrel

may be varied at will, the instrument is readily adaptable for use in any position or on any portion of the body.

Positive massaging may be obtained by use of the member on the end of the wobble shaft, the movements of which are caused by the positive driving connections, and are not checked or deadened in any way by application of the instrument to the person of the user. There is a rocking, kneading or massaging movement produced by the wobble shaft that is entirely distinct from that caused by the weight vibrations. Both the massaging and the vibrating movements may be simultaneously applied to a subject by proper disposition of the several members.

The structure is compact, not liable to become disarranged through use or wear, is readily inspected and adjusted and is easily sterilized and cleansed.

Obviously, changes in the details of construction may be made without departing from the spirit of my invention and I do not care to limit myself to any particular form or arrangement of parts.

What I claim is:—

In an appliance for imparting mechanical vibrations, a hollow closed casing, a manually driven shaft revolvably supported transversely of the outer end thereof, a weight member loosely suspended on the shaft, means operable from the outside of the casing for securing the member to the shaft to revolve out of balance, a sleeve connected to the outer side of said casing and disposed at right angles thereto, a shaft arranged longitudinally of said sleeve and movably held at the outer end of said sleeve, said shaft having the inner end thereof loosely mounted in said driven shaft at a point eccentric to the longitudinal axis thereof, and a massage member detachably mounted upon the outer end of the last mentioned shaft.

In testimony whereof I affix my signature in presence of two witnesses.

FRANK C. DORMENT.
